Primary Examiner — Joseph Kukella*Assistant Examiner* — Lavon M. Amerson(74) *Attorney, Agent, or Firm* — WHDA, LLP(57) **CLAIM**

The ornamental design for an outboard motor for a vessel, as shown and described.

DESCRIPTION

FIG. 1 is a first perspective view of an outboard motor for a vessel, showing our new design;

FIG. 2 is a second perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof; and,

FIG. 8 is a left side elevational view thereof.

The broken lines shown in the drawings depict portions of the outboard motor for a vessel that form no part of the claimed design. The gray scale shading of the drawings depict the shape of the three-dimensional surface and do not represent any particular colors.
